UNITED STATES PATENT OFFICE.

ANDRÉ VARAUD, OF GENEVA, SWITZERLAND.

PERCUSSION FUSE FOR PROJECTILES SUBJECTED TO A ROTARY MOVEMENT AROUND
THEIR AXES DURING THEIR TRAJECTORY.

Application filed June 8, 1926, Serial No. 114,428, and in Switzerland June 9, 1925.

The invention refers to percussion fuses for projectiles subjected to a rotary movement around their axis during their trajectory.

Up to this date the percussion of these fuses has been controlled by impact either by an inertia effect projecting one of two ignition members (striker or primer) one upon the other, or by the axial return motion of a striker disposed at the outside of the fuse point and normally retained by means of a pin or a spring in its position projecting from the fuse point so as to touch the butt or aim before the body of the fuse does so.

In the case of the first described arrangement it is practically observed that the inertia effect counted on does not produce itself with such an energy and rapidity as will be sufficient to cause percussion whenever the projectile arrives at the butt in a rather tangential direction with the ground as will often occur in firing with a very straight trajectory or whenever the projectile falls laterally on the butt in which case the inertia effect is produced too late for rendering the firing really effective if the impact takes place on a network of barbed or steeple wire, in very humid or marshy grounds, or even on a pond or the like, because the projectile in such a case is buried too deep before it bursts.

In the second case referred to, it is possible by a sufficient reduction of the pin or of the spring to increase the sensibility of the fuse so that the projectile bursts fairly near the surface of the ground, even if the encountered obstacle offers but comparatively little resistance, but this increase of sensibility is obtained at the expense of safety in the use of such fuses. In fact it may be stated that in practical use not only is the transport of such fuses very dangerous, but that even a very slight error in the caliber of the pin or in regulating the spring may cause the striker to be returned by the resistance of the air and to thereby provoke a premature bursting of the projectile a number of meters after its start.

Independently of this defect it is observed in both the cases alluded to that a great number of failures occur in the firing with a very straight trajectory, which are due to the fact that upon the impact the projectile simply grazes the ground and re-

bounds without the fuse point meeting an obstacle, an event which often produces a torsion of the bar of the striker and prevents it from freely sliding towards the primer.

In order to overcome these inconveniences, that is to say in order to produce a percussion fuse which, on the one hand, fully warrants entire safety during transport and during firing, and, on the other hand, secures on the impact a sufficiently instantaneous percussion for causing the bursting of the projectile right on the surface of the ground no matter what be the nature of the obstacle met with and the position of the projectile on its arrival, the fuse according to this invention is made to comprise at least one member subjected to the action of the centrifugal power and laterally projecting from the body of the fuse and remaining in this position regardless of the resistance of the air during the entire trajectory and which at the end of the latter will provoke an instantaneous percussion immediately as the least possible resistance displaces it from this projecting position.

The drawing shows by way of example a working form of the invention.

Fig. 1 is an elevation showing the fuse provided with its protecting cap.

Fig. 2 is a similar view representing the fuse with its protecting cap taken off.

Figs. 3 to 6 are axial longitudinal sections showing the fuse respectively before firing, at the moment of firing, at the moment when the projectile traverses the spires in the cannon, during the trajectory and finally at the moment of the impact.

Figs. 7, 8 and 9 are transverse sections respectively on the lines VII—VII of Fig. 2, VIII—VIII of Fig. 4 and IX—IX of Fig. 6.

The Figs. 10 to 12 are detail views.

From the Figs. 1 to 6 it will be seen that the fuse is made from three portions, *a*, *b*, and *c*, screwed one into the other.

The striker *p* is mounted axially movable in the axis of the fuse and is guided by means of a sleeve made in one piece with the part *a*. This striker is normally submitted to the action of a percussion spring *r* which is put under tension in the course of manufacture of the fuse and is maintained in this position until the moment of the impact by means of a swivelling lever *m* provided at

its free end with a portion m^4 having an inclined plane adapted to enter a notch p^2 of corresponding shape provided for in the striker p .

5 It is easily to be conceived that this notch with an inclined surface serves on the one hand to prevent each and every axial displacement of the striker in the direction towards the primer when the lever m^3 is in its locking position, and on the other hand is adapted to facilitate the movement of this lever by the action of the percussion spring r as soon as it is free to the action of the centrifugal power. In order to hold the portion m^4 of this lever m^3 engaged in the notch p^2 of the striker p a locking sleeve g is made use of in the circular hollow g^1 of which enters a pin m^5 fixed on the lever m^3 .

When at rest this sleeve g is prevented 20 from any axial displacement by two cylindrical stoppers n or centrifugal safety members which are provided for in diametrically opposed positions and lodged radially with regard to the axis of the fuse. The inner 25 ends of these stoppers come to bear against the periphery of the locking sleeve g whilst its other ends rest on the internal portions of lever l whose function will be explained later on.

30 These diametrically opposed levers l are arranged in a diametrical slit provided for in the cap b and are adapted to swing on a pin q fixed in the cap b .

Between two shanks l^2 of each of the levers 35 l there is provided a release finger d also oscillating on said pin q .

Each finger d is operated by its lever l by means of a spring e lodged between the shanks l^2 .

40 The part d^1 of this finger remains in mesh with a circular groove of the sleeve g whilst the notch d^2 comes to bear against the free end of spring e .

The operation of this embodiment of the 45 invention is as follows:

Before beginning with the firing, the protecting cap i is removed.

At the departure of the projectile, a cylinder s will take under the action of the inertia effect the active position shown in Fig. 50 4 and the levers l will, also owing to the inertia effect, remain in their lodging flush with the body b of the fuse during the whole linear acceleration which exercises a much

55 more powerful action on said levers l than the angular inertia moment, derived from the rotary movement of the projectile. In other words: since the inertia effect in the direction of the translation is much greater 60 than the angular inertia moment, the levers l conserve their position according to Fig. 4 during the entire duration of the passage of the projectile through the spiral of the cannon.

65 As soon as the projectile leaves the mouth

of the cannon and therefore the linear acceleration has reached its end, the centrifugal power causes regardless of the resistance of the air, the spreading apart of the levers l which will take the slant position 70 as shown in Fig. 5 and the cylindrical stoppers n which pass through the opening b^1 will thus liberate the locking sleeve g . The spreading apart of the levers l has on the other hand brought the free ends of the 75 springs e into the notches d^2 of the two liberating fingers d , the fuse is put under tension so that it will be ready to function at the moment of impact irrespective of the 80 nature of the obstacle met with and no matter what is the position in which the projectile arrives at the butt.

The fuse having thus been put under tension nothing will hinder any longer the axial advance displacement of the sleeve g and 85 this displacement will take place at the end of the trajectory in one of the following manners:

1. Under the action of the inertia effect, which tends to throw the sleeve g forward 90 if the projectile by its point strikes a relatively hard obstacle.

2. Under the action of the folding of the levers l transmitted through the fingers d , in the case that the levers themselves are the first to meet the said obstacle, regardless of the fact if the latter offers but a little resistance as for instance would be the case if striking barbed wire or the like.

3. Under the simultaneous effect of both 100 of these mentioned actions if the obstacle met with is a liquid mass, or very soft ground, as marsh or the like, in which the projectile would easily enter if its bursting were not operated nearly upon grazing the ground owing to the conjunction of the inertia effect acting on the mass of the sleeve g and the folding of the levers which in their spread position offer to the obstacle a contact area which is great enough for securing the 105 small shanks of the two liberating fingers d to be operated by the two shanks of the relatively very long levers which they constitute.

4. Under the simultaneous action of the 115 inertia effect operating on the levers in the direction of folding and the rebounding effect which tends to throw the sleeve g forward when upon arrival at the butt the projectile falls on its head.

I claim as my invention:

1. Percussion fuse for artillery projectiles submitted to a rotary movement around their axes during their trajectory comprising a control member submitted to the action of the centrifugal power in such a manner as 125 to be adapted to become laterally standing out from the body of the fuse and to remain in this standing out position during the whole trajectory, regardless of the action of the resistance of the air, an oscillating mem- 130

- ber for locking the striker constituting a lever adapted to swing in a plane perpendicular to the axis of the fuse and which is provided with a pin operating in the bore of 5 a locking sleeve mounted to be axially movable in the direction of the advance of the projectile and concentric with regard to the striker, said sleeve being held in its active position against the action of a percussion 10 spring during the whole trajectory of the projectile by a device controlled by the displacement of said control member standing out from the body of the fuse during the trajectory of the projectile.
- 15 2. Percussion fuse according to claim 1, in which a centrifugal safety member is mounted in a radial slit for immobilizing the said locking sleeve in its active position until the moment in which the projectile leaves the 20 mouth of the cannon, said safety member being adapted to emerge under the action of the centrifugal power through the said radial slit.
3. Percussion fuse according to claim 1, 25 in which a centrifugal safety member is mounted in a radial slit for immobilizing a locking sleeve in its active position until the
- moment in which the projectile leaves the mouth of the cannon, and in which the control member stands out from the body of the fuse during the trajectory of the projectile and is adapted to hold the said centrifugal safety member in its active position during the passing of the projectile through the spires of the cannon. 30
4. Percussion fuse according to claim 1, in which the control member standing out from the body of the fuse during the trajectory of the projectile is constituted by a lever, a finger being provided which is adapted to become operated by the folding of said lever at the end of the trajectory when it meets an obstacle, in such a manner that a locking sleeve is sufficiently axially displaced as to allow the liberation of a swivelling member 40 locking the striker, a spring being arranged between said finger and the lever in order that upon the projectile leaving the mouth of the cannon, the spreading out of the lever causes the device for putting it under tension to be operative. 45
